HAIR TRIMMER

Norbert Shaeffer, Los Angeles, Calif., assignor, by
mesne assignments, to Roy P. M. Davis, Los
Angeles, Calif.

Application March 21, 1949, Serial No. 82,563

8 Claims. (Cl. 30—30)

1

This invention relates to hair trimmers of the general type employing a sharpened blade movable on the body of a comb. Devices of this character are shown in the copending application of Roy P. M. Davis, Serial No. 691,448, filed August 19, 1946; and in the copending application of Norbert Shaeffer, Serial No. 69,885, filed January 8, 1949.

Among the objects of the present invention are to provide a hair trimmer employing a blade carrier mounted in an improved manner on the comb body to provide a drive device for advancing and retracting the carrier, the drive device having a control knob offset with respect to the comb body.

A more particular object is to provide a "half bridge" member cooperable with the comb body to retain the control knob in position and to provide an improved guide for one end of the blade carrier.

Another object is to provide a control knob which is offset with respect to the comb body so that it projects for a minimum distance beyond the back face of the comb and for a maximum distance beyond the front face of the comb.

Other objects and advantages will appear hereinafter.

In the drawings:

Figure 1 is a top edge view of a preferred embodiment of my invention.

Figure 2 is a side elevation showing the front side of the device.

Figure 3 is an enlarged side elevation partly broken away with the half bridge removed to show the drive device for advancing and retracting the carrier.

Figure 4 is a side elevation partly broken away showing indicia on the half bridge cooperable with an indicator on the carrier for indicating the position of the sharpened blade with respect to the comb body.

Figure 5 is a sectional view partly broken away taken substantially on the lines 5—5 as shown in Figure 3.

Figures 6, 7 and 8 are transverse sectional elevations taken substantially on the lines 6—6, 7—7, and 8—8 respectively as shown in Figure 2.

Figure 9 is an elevation partly broken away with the half bridge removed showing initial insertion of the carrier on the comb body.

Figure 10 is a perspective view showing the manner of assembly of the carrier with respect to the sharpened blade.

Figure 11 is a view showing the underside of the half bridge.

2

Referring to the drawings, the comb body generally designated 10 is provided with a conventional series of comb teeth 11 on one end and two symmetrical series 12 and 13 of comb teeth 11 on opposite sides near the other end of the comb body. A carrier 14 is arranged to slide transversely of the comb body so that the sharpened blade generally designated 15 may be advanced toward either of the series 12 or 13. A rotatable 10 control knob 16 turns a pinion 17, and this pinion meshes with a rack 18 fixed on one side of the carrier 14.

Referring more particularly to the details of construction, the comb body 10 is provided with 15 a lip 19 at one extreme end which forms a guide for the end flange 20 of the carrier 14. The inner end of the carrier 14 is held against the comb body 10 by means of the half bridge member 21 which overhangs a portion of the carrier and 20 provides guide surfaces 22 and 23 therefor. The pinion gear may be conveniently formed on the shaft 25 which is imbedded in the control knob 16 so that the knob and shaft rotate as a unit.

Means are provided for securely anchoring the 25 half bridge 21 with respect to the comb body 10. As shown in the drawings this means includes a 30 pair of protuberances 26 which extend into sockets 27. Marginal lips 28 on the half bridge 21 are provided with slanting surfaces 3 which snap or spring over the parallel mating surfaces 34 provided on the comb body. Spaced lugs 5 engage the side wall 6 for increasing frictional resistance against separation of the bridge 21 from the comb body 10. It is important that the 35 half bridge remain securely fixed to the comb body, and I have found that the protuberances 26, lips 28, and lugs 5 are adequate to prevent disassembly of the parts.

The shaft 25 is rotatably supported in cooperating bearing surfaces 28 and 29, each of which is formed one-half in the comb body 10 and one-half in the half bridge 21. Additional cooperating surfaces 30 are formed in the comb body 10 and half bridge 21 to define a window 31 in which the control knob 16 operates. The axis of the shaft 25 is offset with respect to the longitudinal axis of the comb body so that as clearly shown in Figure 6 the knob projects for a greater distance from the forward face 32 of the comb than 40 from the back face 33. An important feature of this construction is that a relatively large size control knob 16 may be employed for easy manipulation between the thumb and forefinger of the user, and yet this knob projects only a 45 minimum distance from the rear face 33. This

rear face lies against the head of the user both when the blade 15 is used in conjunction with the teeth 12 and in conjunction with the teeth 13. A minimum rearward projection of the knob is therefore highly advantageous. On the other hand, projection of the knob from the forward face 32 has no disadvantage since there is adequate clearance on this side.

The knob 16 is preferably formed with a plurality of flat sides 34, and furthermore the knob may be tapered so that one end is larger than the other if desired. The carrier 14 may be provided with a pair of spaced lugs 35 adapted to enter the ends of the longitudinal slot 36 formed in the sharpened blade 15. Transverse grooves 37 are formed in the comb body 10 to provide clearance for the projecting portions of the lugs 35. The member 21 is termed a "half bridge" to distinguish it from constructions in which this member extends from the control knob 16 to the end of the comb body adjacent the lip 19. In the latter construction the full bridge encloses the carrier 14 and blade 15 for their full length. The present construction is superior in that the half bridge is of substantially smaller size and hence less expensive to manufacture and install.

It will be noted that the rack 18 is positioned between the pinion 17 and the comb body 10 and does not lie between the pinion 17 and the half bridge 21. This feature is particularly advantageous because turning of the control knob 16 does not apply forces which would tend to separate the half bridge 21 from the comb body 10. The force of the thumb of the user applied through the knob 16 on the forward side 32 of the device passes through the pinion 17 and rack 18 directly to the comb body 10. Substantially all of the reaction force between the teeth of the pinion 17 and the teeth of the rack 18 is taken by the thumb of the user.

The device is assembled by placing the knob 16 and shaft 25 in position and then installing the half bridge 21 on the comb body 10 to maintain the knob and shaft in position. The blade 15 is mounted on the carrier 14 and the two are assembled as a unit onto the comb body by inserting the end guide 38 in the groove 39 and inserting the guide flange 20 under the lip 19. The carrier 14 and blade 15 are then transversely moved manually so that the rack 18 enters the recess 24 and engages the pinion 17. Further movement of the carrier and blade may be accomplished by rotating the knob 16 between the thumb and forefinger. An indicator 40 on the carrier 14 may coact with suitable indicia 41 formed on the exposed surface of the half bridge 21 to indicate the relative position of the blade 15 with respect to the comb body 10. Since the series of comb teeth 12 and 13 are symmetrical and since the carrier 14 is mounted for transverse movement between them, the same degree of projection of one of the sharpened edges of the blade 15 may be obtained on either side of the comb. When the carrier 14 is in the central position neither of the edges of the blade 15 projects between comb teeth, and hence the blade is inoperative. By progressively turning the knob 16 in either direction the blade may be successively moved from a thinning position through various cutting positions to the fully extended position for shaving.

Having fully described my invention, it is to be understood that I do not wish to be limited to the details herein set forth, but my invention is of the full scope of the appended claims.

I claim:

1. In a hair trimmer, the combination of: a comb body, a member attached to the comb body intermediate the ends thereof cooperating with the comb body to form a recess, a rotatable control knob, a pinion gear in the recess secured for rotation with said knob, a carrier for a sharpened blade mounted for transverse sliding movement on the comb body, the carrier having a guide rail received in said recess, and a rack formed on the end of the carrier adjacent the guide rail and positioned between the pinion gear and the comb body whereby rotation of the knob and gear serve to advance and retract the carrier.
2. In a hair trimmer, the combination of: a comb body, a member attached to the comb body intermediate the ends thereof cooperating with the comb body to form a recess, said member and the comb body having aligned openings forming a window, a rotatable control knob positioned within said window, a pinion gear in the recess secured for rotation with said knob, a carrier for a sharpened blade mounted for transverse sliding movement on the comb body, the carrier having a guide rail received in said recess, and a rack formed on the end of the carrier adjacent the guide rail and positioned between the pinion gear and the comb body whereby rotation of the knob and gear serve to advance and retract the carrier.
3. In a hair trimmer, the combination of: a comb body having a lip at one end defining a groove, a member attached to the comb body intermediate the ends thereof cooperating with the comb body to form a recess, said member and the comb body having aligned openings forming a window, a rotatable control knob positioned within said window, a pinion gear in the recess secured for rotation with said knob, a carrier for a sharpened blade mounted for transverse sliding movement on the comb body, the carrier having a flange slidably mounted in said groove and a guide rail received in said recess, and a rack formed on the end of the carrier adjacent the guide rail and positioned between the pinion gear and the comb body whereby rotation of the knob and gear serve to advance and retract the carrier.
4. In a hair trimmer, the combination of: a comb body having a lip at one end defining a groove, a half-bridge member attached to the comb body intermediate the ends thereof cooperating with the comb body to form a recess, the half-bridge member having a guide channel in said recess, said member and the comb body having aligned openings forming a window, a rotatable control knob positioned within said window and projecting from both sides thereof, a pinion gear in the recess secured for rotation with said knob, a carrier for a sharpened blade mounted for transverse sliding movement on the comb body, the carrier having a flange slidably mounted in said groove and a guide rail received by the comb body within said recess, the carrier also having a guide rail slidably received within said guide channel, a rack formed on the end of the carrier and positioned between the pinion gear and the comb body whereby rotation of the knob and gear serve to advance and retract the carrier.
5. In a hair trimmer, the combination of: a comb body having a lip at one end defining a groove, a member attached to the comb body intermediate the ends thereof cooperating with the comb body to form a recess, said member and the comb body having aligned openings forming a window, a rotatable control knob positioned

within said window, the knob being offset with respect to the comb body so that it projects rearwardly through the window for a relatively small distance, a pinion gear in the recess secured coaxially to the knob for rotation therewith, a carrier for a sharpened blade mounted for transverse sliding movement on the forward side of the comb body, the carrier having a flange slidably mounted in said groove and a guide rail received in said recess, and a rack formed on the end of the carrier adjacent the guide rail and positioned between the pinion gear and the comb body whereby rotation of the knob and gear serve to advance and retract the carrier.

6. In a hair trimmer, the combination of: a comb body, a member attached to the comb body intermediate the ends thereof cooperating with the comb body to form a recess, a rotatable control knob offset with respect to the comb body and rotatable about an axis parallel to the longitudinal axis of the comb body, a pinion gear in the recess secured for rotation with said knob, a carrier for a sharpened blade mounted for transverse sliding movement on the comb body, the carrier having a guide rail received in said recess, and a rack formed on the end of the carrier adjacent the guide rail and positioned between the pinion gear and the comb body whereby rotation of the knob and gear serve to advance and retract the carrier.

7. In a hair trimmer, the combination of: a comb body, a member attached to the comb body intermediate the ends thereof cooperating with the comb body to form a recess, said member and

the comb body having aligned openings forming a window, a rotatable control knob positioned within said window and rotatable about an axis parallel to the longitudinal axis of the comb body, 5 said member and the comb body also having aligned openings forming spaced bearings for the rotatable control knob, a pinion gear in the recess secured for rotation with said knob, a carrier for a sharpened blade mounted for transverse sliding 10 movement on the comb body, the carrier having a guide rail received in said recess, and a rack formed on the end of the carrier adjacent the guide rail and positioned between the pinion gear and the comb body whereby rotation of the knob and gear serve to advance and retract the carrier.

8. In a hair trimmer, the combination of a comb body, a half bridge member attached to the comb body intermediate the ends thereof cooperating with the comb body to form a recess, 20 the half bridge member and the comb body each having a guide channel positioned in said recess, a carrier for a sharpened blade mounted for transverse sliding movement on the comb body, the carrier having a first guide rail received within the channel on the comb body and a second guide rail received within the channel on the half bridge member, and cooperating parts including a pinion gear meshing with a rack formed on the carrier for advancing and retracting the carrier 25 relative to the comb body.
